Attn:

UNITED STATES PATENT OFFICE.

ROBERT T. JOHNSTON, OF NEW BRUNSWICK, NEW JERSEY, ASSIGNOR TO THE FLINT-KOTE COMPANY, OF BOSTON, MASSACHUSETTS, A CORPORATION OF MASSACHUSETTS.

MACHINE FOR MAKING ASPHALT SHINGLES.

Application filed March 20, 1923. Serial No. 626,442.

Machines now in use for the manufacture of asphalt shingles, such as are made of felt saturated and coated with asphalt and often surfaced with crushed slate, or similar material, commonly range in length from 150 to 200 feet, the tendency being toward longer machines to provide a longer time to properly cool the sheet. The greater portion of this length is taken up by the saturating and cooling mechanisms. These machines also require from 18 to 20 feet of head room to accommodate the looping and festooning devices of the cooling mechanism.

The total length of sheet material in these machines averages over 1000 feet, the proportion being 650 feet in the loops and festoons and 350 feet in the remainder of the machine.

The movement of the sheet through this machine is not continuous, the several mechanisms not being geared together, the festooning mechanism separating the mechanism for cutting the sheet into shingle units from the saturating and coating mechanisms. For this reason an operator is required to feed the sheet by means of a clutch mechanism from the festooning devices to the cutting and delivery devices as it is needed.

Owing to the very long space required for these machines and the great length of the web, it is the practice in many roofing plants to divide the machine into two entirely separate units, saturating the sheet and rewinding it into rolls in one machine and coating and slating the previously saturated sheet and cutting it into finished units in another machine. A serious shortcoming of these machines is the loss of paper and other materials in first threading the machine and from the constant breakages of the very long sheet, also in the production of defective and partially defective goods resulting from the lack of continuity of operations. Slowing down or stopping the sheet even momentarily causes it to scorch in the saturating tank and the coating to congeal before the slate is applied and also the coating and slating to be unevenly applied, and as the exact location of the defective goods is not readily discernible, a greater quantity of finished goods than are actually spoiled must be discarded or sold as seconds. Much of the material thus partially treated is not in condition to be sold as seconds and has no salvage

value since the presence of asphalt therein renders it impracticable to prepare it for reclamimation and utilization in the paper machine.

The present invention has for one of its objects the provision of a machine comprising a plurality of properly synchronized mechanisms so constructed and related that the total length of the machine may be materially shortened and the necessary head room reduced. The decrease in length and height of the machine is accomplished by the employment of intensive methods of saturation and cooling, and by properly synchronizing the various mechanisms the product may be made of substantially uniform quality and with less labor than heretofore.

A further and very valuable feature of the invention relates to means whereby the felt is automatically removed from the saturant when it is desired to stop the machine, the felt already saturated being coated, surfaced and otherwise completed before the entire machine comes to rest, the machine being then threaded with dry felt in preparation for subsequent operation. When the machine is again started, the felt is again returned to the saturant and the usual later operations then resumed automatically in proper timed relation.

By this means substantially all the waste material comprises the dry felt extending beyond the saturator when the machine is stopped which is salvaged and returned to the paper machine to be again felted into sheet material.

The machine when stopped is thus ready threaded for immediate resumption of operations and substantially none of the material treated thereby is incompletely treated forming sections of unreclaimable waste.

Means is also provided for controlling the various mechanisms independent of the automatic means to provide for initial adjustment, testing, or other purposes.

The various mechanisms may also be assembled as complete units so that as improved units are developed they may be substituted for the former ones without disturbing others in the machine.

Many other advantages result from this invention, among which might be mentioned the increased capacity of a plant per unit of floor space, fewer operatives necessary for

proper operation, and decreased liability of breakage of the felt web and consequent waste, delay, and non-conformity of the quality of the product.

5 Further objects and advantageous details and combinations of parts will appear from a more complete description of an embodiment thereof shown in the accompanying drawings in which

10 Figure 1 is a diagrammatic side elevation showing the various operating mechanisms assembled for the complete machine.

Figure 2 is a diagram of driving mechanisms and control circuits therefor.

15 Figure 3 is a detail of a magnetic clutch release.

Figures 4 and 5 are elevational details of a valve-actuating mechanism.

20 Figure 6 is a vertical section through an automatic starting and stopping controller.

Figure 7 is an elevational detail thereof.

Referring first to Figure 1, the felt enters the machine either from a roll or directly from the paper machine, as desired, at the right hand end. As shown it first traverses a series of drier rolls A, though with certain types of saturating mechanism it may be unnecessary to employ these driers. However, they are here shown as they might be

30 necessary or desirable in certain instances. From the rolls A the web of felt W passes to the saturator B. As shown this saturator is of the vacuum type disclosed and claimed in my application for patent Serial No. 626,439, filed March 20, 1923. It might, however, be of any other suitable type in which the saturation is effected by intensive methods instead of being passed through an open saturating tank under atmospheric pressure.

40 Other saturators adapted to carry out intensive methods of saturating are disclosed and claimed in my applications for patent Serial Nos. 445,877 and 445,878, filed February 17, 1921. The saturator shown will be described more in detail but it is sufficient at the present time to state that it not only saturates but coats the web of felt with asphalt and has provision by which the web may be removed or immersed in the saturant

50 as may be desired.

After passing through the saturating and coating mechanism B the web passes to a suitable coating or surfacing device for applying the slate or other granular surface material. This is shown at C and may be of any suitable or usual type. As shown it comprises a supply hopper 1 and a distributing hopper 2, the distributing hopper having rotatable therein an agitator 3, the parts being so designed that while the agitator 3 is being rotated the granular material is sifted down on the upper face of the web, but on stopping the motion of the agitator the application of the granular material ceases.

65 Next the web passes to a suitable cooling

means shown at D. While this cooling means might be of any desired type in which cooling may be effected rapidly, as shown it is of the type described more fully and claimed in my application Serial No. 629,225, filed March 31, 1923. For present purposes it will be sufficient to state that this cooler comprises two pairs of upper and lower feed rolls 10 and 11 between which is interposed an inclined table 12 carrying a series of 70 pipes 13 perforated in their upper faces through which water may be flowed upwardly into contact with the lower face of the sheet material which passes down thereover. The water is supplied in sufficient 75 volume to insure cooling of the sheet by the time it reaches the lower end of the table, the water not being driven off in the form of steam flowing down to a drain tank 14 from which it is removed. The web of material 80 then being cool, but wet, is passed over an air jet 15 which causes the adherent water to be blown therefrom and then as it passes upwardly over the adjacent feed roll 11, a series of flame jets from pipes 15^a impinge 85 thereagainst, this serving to vaporize the remaining moisture on the sheet, the material passing these jets so rapidly that the heating effects only its surface, the heat being readily absorbed by the main body of the 90 web which is delivered to the succeeding mechanisms in cool and dry condition.

Next the web may pass to a talc or mica-applying device shown at E which may be of any suitable type, preferably similar to the 100 vacuum machines for applying bronze powder such as are commonly employed in connection with printing presses. This device is shown only diagrammatically since it has no power operating means and does not 105 therefore enter into the sequential control of the various mechanisms such as will be described. This coating mechanism E is shown as supported from the cutting mechanism F by which the web is cut into the shingle units as desired and from which they are delivered to any suitable counting and packaging mechanism, shown at G. These mechanisms may be of well known form and will 110 therefore not be further described.

Referring now to Figure 2 the drive mechanism for the various units is diagrammatically indicated. At 20 is shown a driving motor by which all the mechanisms are actuated, this motor being shown as driving 115 a main shaft 21. The drying rollers A are driven from the main shaft 21 by means of gearing 22 which may be clutched to the shaft 21 by means of an electrically actuated clutch 23. In alignment with the shaft 21 120 is a second shaft 24 which may be clutched to the shaft 21 through a similar clutch 25. Driven by the shaft 24 through gearing 26 is a shaft 27 for driving the feed mechanism of the saturator, it being preferable to inter- 125

pose in this drive a manually actuatable clutch 28. A shaft 30 for driving the slating device is also driven through gearing 31 and a magnetic clutch 32 by the shaft 24.

5 A pair of shafts 33 each preferably having a manually operable clutch therefor are geared by a gearing 34 to the shaft 24 and are connected to drive the feed rolls 10 and 11 of the cooling mechanism. Similarly

10 shafts 35 and 36 are connected through gearing 37 and 38 to the shaft 24 to the slitting and chopping devices of the mechanism F, and the mechanism G may be also driven therefrom.

15 The various manually operable clutches above mentioned are shown as of the friction type, and they may, if desired, be so designed as to allow slip in case the tension on the web at any point should become excessive. The various mechanisms may thus be so driven as to exercise a gentle draft on the material sufficient to feed it properly without danger of breakage.

The clutches 23, 25, and 32, as shown, are

20 electrically operated for the purpose of permitting them to be controlled successively in order to stop and start the various mechanisms in definite sequential orders. For throwing these clutches into clutching engagement are shown electromagnets or solenoids 40, 41, and 42, while the clutches are normally held out of engagement by springs indicated at 43, 44, and 45. These clutches may be held in engagement after having been

25 thrown therein by the energization of their respective actuating magnets by latch mechanisms, such as is shown in Figure 3 in which a clutch lever shown at 50, normally held in un-clutching position by means of a spring

30 51, when thrown into clutching position passes beyond a latch hook 52 of a latch lever 53 pivoted at a fixed point 54 and which drops into position to hold the lever 50 in clutched position shown in dotted lines. With this construction it is unnecessary, therefore, to maintain the actuating magnet energized to hold the clutch in engaging position, it being only necessary to throw the clutch into engaging position

35 whereupon the latch so retains it. Means are provided for releasing the latch to permit the clutch to open, such means comprising a solenoid 55 positioned above the latch hook 52 and by the energization of which

40 this hook 52 is raised out of engagement with the lever 50, whereupon the spring 51 immediately throws it to unclutched position. Such a clutch control is employed for each of the clutches 23, 25, and 32 of Figure

45 2, the release solenoids for the latches being indicated at 60, 61 and 62, respectively.

Besides the control of the driving devices of the various mechanisms, it will be noted that, as before stated, the saturator may be

50 manipulated to immerse the web of material

within the saturant or to raise it therefrom. As shown in Figure 1, the saturator comprises a tank 70 for containing the saturant having at opposite sides vertically extending throats 71 through which the web may

55 pass into and out of the tank. These throats may be closed more or less by a pair of gates 72, each gate having a feed roller 73 at its lower end which, when the gates are closed, cooperates with a lower feed

60 roller 74 to feed the web. The roller 74 is always positioned beneath the level of saturant in the tank 70, this tank being supported in an outside tank 75 into which the web is initially led before passing into the

65 tank 70 and out of which it is led after passing therethrough. Within the tank 70 is also a lower feed roller 76 with which cooperates an upper roller 77. The roller 77 is vertically movable within the tank, being

70 carried to move along a threaded rod 78 projecting through the top of the tank 70 and having a gear 79 thereon. The gates 72 also engage threaded rods 80 having gears

75 81 at their upper ends and between the gates

80 72 and the upper and lower feed rollers within the tank are positioned guide bars

85 82 which are also vertically adjustable on threaded rods 83. These rods also have gears at their upper ends so that by rotation of any one of the gears all the threaded rods are rotated in unison in such manner that as the upper rollers 73 and 77 are raised the bars 82 are lowered until these parts take the position shown in dotted lines where

90 they are entirely above the level of the saturant. The web is then fed under the rollers 73 and 77 and over the bars 82, being entirely out of the saturant. When the bars are raised and the upper feed rollers lowered, it is evident that the web is immersed in the saturant adjacent to the rollers but it extends out of the saturant over the bars 82. This is the normally operative position

95 of the parts in which the saturation is effected by passing the web into the saturant in the tank 75 beneath the first upper feed roller 73 and then alternately out of and into the saturant in the tank 70 and finally out of tank 70 beneath the level of the saturant in the tank 75 where it is coated as it

100 passes to any suitable form of scraper or doctor as at 85 by which the thickness of the coating is determined.

105 For the purpose of rotating the threaded rods a shaft 88 is shown which is adapted to be rotated in reverse directions by means of a motor M, shown in Figure 2. When it is desired to stop the machine, therefore, in order that the web may not be injured by

110 too long a treatment with the hot saturant, it should immediately be raised therefrom and then in order that the coating and surfacing with the slate or granular material should be applied at the proper time, the material

115

120

125

130

saturated should also be immediately further treated as though the machine were not to be stopped. If this is done the web already saturated is completely finished, the 5 web feeding into the saturator thereafter being fed above the level of the saturant therein so that it is not treated by the saturant. As this unsaturated material reaches the surfacing, cooling, and cutting means 10 these may be stopped leaving the machine completely threaded with dry felt by the time it is entirely stopped. Likewise in starting the machine, it being assumed that the machine is already threaded with the 15 felt, the first action should be to immerse the felt in the saturant in order that the treatment may be started and then the further operations should be performed on the saturated portion in proper sequential order. 20 For the purpose of controlling the mechanisms in this relationship, an automatic means is provided by which the sequential stopping of the various mechanisms may be initiated when it is desired to stop the machine to leave in the machine when it finally 25 stops, untreated felt, this mechanism being also operative to initiate the actions of the various mechanisms in their proper order to treat the felt with the saturant and then 30 to effect the proper later operations. Such a mechanism is indicated in detail in Figures 6 and 7 and diagrammatically in Figure 2. Referring to these figures, 90 indicates a controller drum fixed to rotate with 35 a shaft 92 within a casing 93. Also fixed to the shaft 92 is a worm wheel 94 with which meshes a worm 95 fixed to a shaft 96 of a motor 97. This motor 97 is controlled through a manual switch comprising a contact 98 carried by a lever 99 and which may 40 be projected between a pair of spring contacts 100 to close the circuit to the motor. By rotation of this motor the drum 90 is rotated with a definite slow speed in one 45 direction and this drum 90 is formed to serially effect the making of contacts in order to control the electric clutches for the various mechanisms and the motor M. The switch lever 99 has fixed thereto a button 50 101 which may be depressed by the operator to start the rotation of the drum 90. In order to insure the stopping and starting of this drum in proper relation to the various contacts, it may be provided with a 55 flange 102 having a pair of notches 103, 104 therethrough so designed as to permit one end of the lever 99 to pass therethrough. When one of these notches is in position for the lever to pass therethrough, the drum 60 is in machine running or stopped position. In either case if the button 101 is depressed to close the circuit of the motor 97 the drum 90 starts its rotation and the flange 102 passes in the way of the lever 99 so as to 65 prevent the breaking of the motor control

circuit until the next notch 103 or 104 is reached at which time a spring 105 acts to throw out the contact 98 whereupon the motor 97 stops.

The drum 90, as above stated, is provided with contacts for properly energizing the solenoids of the magnetic clutches and for energizing the motor M. For this purpose it is in electrical connection with one side of a control circuit through a slip ring 110 with which engages a brush 111 leading to one side of a suitable source of potential T. At 112 is shown a bar of insulating material carrying a series of brushes contacted in proper order by a series of contacts on the drum, these brushes leading to the solenoids of the clutches and to the motor as will be described. The solenoid 40 for throwing in the clutch 23 is connected to the brush a and to the opposite side of the source of potential from the brush 111. The release solenoid 60 for this clutch is similarly connected to the brush b. The brushes c and d may be connected in manners to be later described to the motor M. The brush e connects to the release solenoid 62. The brush f connects to the clutch-actuating solenoids 41 and 42. The brush g connects to the release solenoid 61.

For the purpose of controlling the motor M to raise and lower the web, a motor reverse mechanism has been devised. Referring to Figure 1 it will be noted that one of the gates 72 has fixed to move therewith a rod 115 which is slidably guided at its upper end. This rod has fixed thereto a pair of spaced abutments 116 and 117 adapted to impinge on an arm 118 of a reversing switch shown diagrammatically at S in Figure 2. While the connections may be made in any suitable manner, as shown this switch is so connected as to reverse the electrical connections to the armature of the motor, the terminals thereof being shown at l, m, and n. As the gates are lowered the abutment 117 engages the switch arm and by moving it disconnects the armature from the terminals m and n and connects as shown in full lines in Figure 2, the terminals m and l, the terminal m being connected to the opposite side of the armature circuit from its previous connection. The terminal l is connected to the brush c and the terminal n to the brush d, hence if the switch is in the dotted line position of Figure 2 and the brush d be contacted with a segment on the drum, the motor M is rotated in a direction to lower the gates 72, which as above noted, lowers the feed rolls and raises the bars 82 to immerse the web in the saturant. When the web is in immersed condition the abutment 117 striking the switch arm acts to reverse the switch S, disconnecting the terminal n and establishing connection with the contact l. As this breaks the connection to the

brush *d*, the motor immediately stops, but when the circuit is again closed through the contact *l* by means of the brush *c* contacting with a segment on the drum, the motor is 5 energized to rotate in the reverse direction to raise the web out of the saturant, this taking place until the abutment 116 throws the reverse switch to its opposite position, stopping the rotation of the motor and leaving 10 it in connection to be rotated in the opposite direction when contact is again made through the brush *d*.

Assuming that the machine is to be started and the drum 90 is rotated by the motor 97 15 in the direction shown by the arrow in Figure 7, depression of the button 101 starts the rotation of the drum from the position shown in Figure 7 to a position where the lever 99 may pass through the slot 104. As 20 shown the sequence of action is as follows. Contact is first made through the brushes *a* and *c* so that the solenoids 40 are energized to start the rotation of the mechanism A and to start the rotation of the motor M to immerse the web in the saturant. The material 25 is then fed from the drier A to the saturator, this material being taken up in the increase in the length of web when the web is immersed in the saturant. As soon as the web 30 is fully in its normal saturation path, feed of the rest of the machine is effected through the energization of the solenoid 41 through the contact *f* and at the same time the slating device is set in operation by the energization 35 of the solenoid 42. The throwing of the clutch 32 may also serve to turn on the water for the cooler D and also the gas for the flame 15^a, it being desirable to employ a pilot light for igniting the gas as 40 soon as it is turned on. The machine now is in its normal running condition, the drum 90 being stationary in the lever 99 engaging with the slot 104. When it is desired to stop the machine the button 101 is again de- 45 pressed, whereupon the motor 97 starts further rotation of the drum 90. The first action in stopping is to start the raising of the web from the saturant by energization of the motor M through the contact brush *d* 50 and also to stop the action of the drier A in feeding material to the saturator by releasing the clutch 23 by contact with brush *b*. By this means the material in the saturator is taken up through the succeeding mechanisms as the web is removed from the saturant. As soon as this has been effected the motion 55 of the drier A is again resumed by contact of the brush *a* so as to feed the material through the machine in order to permit all 60 the web already saturated and coated in the saturant, to be surfaced, cooled, coated with talc, cut and finished.

As soon as the saturated and coated material passes the surfacing mechanism C, the clutch release solenoid 62 is energized

through the brush *e*, thus stopping the slating, and as shown, at the same time the water supply, air and gas are cut off by the movement of the clutch lever which may actuate control valves 150, 151, and 152 70 therefor in the manner clearly shown in Figures 4 and 5. As shown in these figures the air and gas valves 150 and 151 are mounted in a common valve casing, while the water valve 152 is shown as in a separate casing. 75 All three might be in a single casing or they might be separate with a common stem if desired however, if they are intended to be actuated simultaneously. As shown the stems of these valves have actuating arms 80 153 having pins 154 thereon projecting in slots 155 in the clutch lever 50. If desired the water, gas and air might be controlled by the clutch 25 instead of by the clutch 32, or the water might be controlled by the 85 clutch 32 and the air and gas by the clutch 25. The feed of the web then continues until the material saturated has been completed and then the entire mechanism stops, the solenoids 60 and 61 being then energized by 90 contact of their respective control brushes with drum segments. This leaves the machine when stopped with a web of dry felt threaded therethrough in condition to resume operations immediately when desired 95 according to the cycle above described.

It is preferable that the circuits through the various control solenoids for the clutches may be controlled independently of the automatic mechanism and for this purpose manually operated switches for each circuit have been indicated grouped at J. The provision of these switches and the various manually actuable clutches is for the purpose of permitting the mechanisms to be controlled independently of each other as for the purpose of adjustment, repairs and the like and to permit the web to be initially placed in the machine in proper condition. When the web has been so placed these manual clutches and 105 switches are thrown to their normal positions and the automatic control of the mechanisms is then utilized.

While particular cycles have been described, it should be evident to those skilled in the art that the mechanisms might be arranged to function in somewhat different order if desired and that many other changes and modifications might be made therein without departing from the spirit or scope 110 120 of this invention as defined by the appended claims.

I claim:

1. A machine of the class described, comprising mechanisms for progressively saturating a continuous strip of fibrous material and for performing different operations successively on the saturated material for the production of roofing elements, means for driving said mechanisms, and means for 121

automatically disconnecting said mechanisms sequentially from said driving means in stopping the machine.

2. A machine of the class described, comprising mechanisms for progressively saturating a continuous strip of fibrous material and for performing different operations successively on the saturated material for the production of roofing elements, means for 10 driving said mechanisms, and means for automatically disconnecting said mechanisms sequentially from said driving means in stopping the machine and for automatically associating said mechanisms and driving 15 means sequentially in starting the machine.

3. A machine of the class described comprising saturating mechanism, other mechanisms for performing operations on the saturated material, means to drive said 20 mechanisms, and means for automatically disconnecting said mechanisms successively from said driving means in stopping the machine in such relation that substantially all the material saturated is also treated by 25 the other mechanisms.

4. A machine of the class described comprising mechanism for progressively saturating a length of fibrous material, other mechanisms for performing different operations successively on the material, means 30 for driving said mechanisms, and means for automatically disconnecting said mechanisms sequentially from said driving means in stopping the machine in such relation that substantially all the material saturated is also treated by said other mechanisms and that untreated fibrous material remains threaded through said mechanisms when the machine has stopped.

40 5. A machine of the class described comprising mechanism for progressively saturating a length of fibrous sheet material; other mechanisms for performing different operations successively on the material, 45 means for driving said mechanisms, and means for automatically disconnecting said mechanisms sequentially from said driving means in stopping the machine in such relation that substantially all the material saturated is also treated by said other mechanisms and that untreated fibrous material remains threaded through said mechanisms when the machine has stopped.

55 6. A machine of the class described comprising saturating and coating mechanism, and surfacing mechanism arranged to act successively on fibrous material, means for driving said mechanisms, and means for automatically disconnecting said mechanisms 60 sequentially from said driving means in stopping the machine in such relation that substantially all the fibrous material saturated is also coated and surfaced.

65 7. A machine of the class described comprising saturating mechanism, coating mech-

anism, surfacing mechanism and cutting mechanism arranged to act successively on fibrous material, means for driving said mechanisms, and means for automatically disconnecting said mechanisms sequentially 70 from said driving means in stopping the machine in such relation that substantially all the fibrous material saturated is also coated, surfaced, and cut.

8. A machine of the class described comprising saturating mechanism, coating mechanism, surfacing mechanism, cooling mechanism and cutting mechanism, arranged to act successively on fibrous material, means for driving said mechanisms, and means for 80 automatically disconnecting said mechanisms sequentially from said driving means in stopping the machine in such relation that substantially all the fibrous material saturated is also coated, surfaced, cooled and 85 cut.

9. A machine of the class described including a mechanism for saturating sheet material having a saturant containing tank, and means for automatically removing the 90 sheet material from the saturant in said tank when the machine is being stopped.

10. A machine of the class described including a mechanism for saturating sheet material having a saturant-containing tank, 95 and means for automatically removing the sheet material from the saturant in said tank when the machine is being stopped, and for automatically returning the material into the saturant as the machine is being 100 started.

11. A machine of the class described comprising mechanism for progressively saturating a length of fibrous material including 105 a tank for saturant through which the fibrous material may pass, and devices whereby the material may be immersed in the saturant or removed therefrom, and mechanisms for performing other operations successively on the material after passing said saturating 110 mechanism; means to drive said mechanisms, and means acting automatically when the machine is being stopped to actuate said devices to remove the material from the saturant and to sequentially disconnect said 115 mechanisms from said driving means in such relation that substantially all the material saturated is also treated by said other mechanisms and that untreated fibrous material remains threaded through the machine 120 when the machine has stopped.

12. A machine of the class described comprising mechanism for saturating and coating fibrous sheet material with melted asphaltic material, mechanism for applying 125 granular material to one face of the coated sheet while hot and partially embedding the granular material in the coating, means for flowing water on the opposite face of the sheet to cool the same, and means for surface 130

- heating said opposite face to dry off water adhering thereto, said mechanisms being arranged to act successively on the sheet material as it is fed therethrough.
- 5 13. A machine of the class described comprising mechanism for saturating and coating fibrous sheet material with heated asphaltic material, mechanism for applying granular material to one face of the coated sheet while hot and partially embedding the granular material in the coating, means for flowing water on the opposite face of the sheet to cool the same, and means for surface heating said opposite face to dry off water adhering thereto, said mechanisms being arranged to act successively on the sheet material as it is fed therethrough and common means for driving certain of said mechanisms.
- 10 14. A machine of the class described comprising mechanism for saturating and coating fibrous sheet material with heated material, mechanism for applying granular material to one face of the coated sheet while hot and partially embedding the granular material in the coating, means for flowing water on the opposite face of the sheet to cool the same, means for surface heating said opposite face to dry off water adhering thereto, said mechanisms being arranged to act successively on the sheet material as it is fed therethrough.
- 15 20 14. A machine of the class described comprising mechanism for saturating and coating fibrous sheet material with heated thermoplastic material, means for flowing water on one face of the sheet to cool the same, and means for surface-heating said face to dry off water adhering thereto, said means being arranged to act successively on the sheet material as it is fed therethrough.
- 25 30

cessively on the sheet material as it is fed therethrough, common means for driving certain of said mechanisms, and means for automatically connecting and disconnecting said mechanism in definite sequence when the machine is respectively started and stopped.

16. A machine of the class described comprising mechanism for saturating and coating fibrous sheet material with melted asphaltic material, mechanism for applying a granular facing to the coated sheet material, mechanism for flowing water on the sheet to cool the same, and mechanism for surface-heating the material to drive off water adhering thereto, said mechanisms being arranged to act successively on the sheet material as it is fed therethrough.

16. A machine of the class described, comprising means for saturating and coating fibrous sheet material with heated thermoplastic material, means for flowing water on one face of the sheet to cool the same, and means for surface-heating said face to dry off water adhering thereto, said means being arranged to act successively on the sheet material as it is fed therethrough.

In testimony whereof I have affixed my signature.

ROBERT T. JOHNSTON.
